UNITED STATES PATENT OFFICE.

JOHN A. BLAIR, OF STEUBEN TOWNSHIP, CRAWFORD COUNTY, PENNSYLVANIA.

ATTACHMENT FOR MILK-PAILS.

1,062,532.

Specification of Letters Patent.

Patented May 20, 1913.

Application filed May 20, 1912. Serial No. 698,472.

To all whom it may concern:

Be it known that I, JOHN A. BLAIR, a citizen of the United States, and a resident of Steuben township, in the county of Crawford 5 and State of Pennsylvania, have invented a new and Improved Attachment for Milk-Pails, of which the following is a full, clear, and exact description.

My invention relates to attachments for 10 milk pails and, more particularly, it is directed to a simple and efficient device for holding a strainer in position across the open top of a milk pail.

The principal object of my invention is to 15 provide an attachment for milk pails, of simple design and make-up, and which may be produced at a low cost, whereby such attachments may be sold for little money.

Reference is to be had to the accompany- 20 ing sheet of drawings, forming a part of this specification, in which similar characters of reference denote corresponding parts in all the views, and in which—

Figure 1 is a side view of a pail with the 25 attachment in operative position; Fig. 2 is a perspective view of the attachment; Fig. 3 is a perspective view of a modified form.

Any suitable and desirable milk pail 10 has the filter cloth or strainer 11 held over 30 the open end thereof by means of the attachment which may be denoted as a whole by 12.

The attachment preferably comprises a 35 single strip 13 of resilient material, pref- erably of uniform thickness and width throughout its length. Extending laterally from one side of this strip are a number of hooks 14, each of which is made up of the shank 15 and the overturned end 16. The 40 overturned ends 16 are all adjacent the same side of the strip so that, when the same is brought to curved form, as shown in Fig. 2, they will lie on the inside of the circle de- scribed by this strip.

Referring particularly to Fig. 2, it will 45 be noted that the ends of the strip 13 where they come adjacent each other are bent out- wardly, as at 20, in order to form a con- venient gripping means for taking hold of 50 the attachment; it is also desirable that, in order to render the device most efficient, the intermediate portion of the strip 13 be of

greater width than the portions to either side thereof.

The use of the device is apparent from 55 Fig. 1, it being noted that the filter or strainer 11 will be held in position by means of the resilient strip bearing against the outside of the pail, the position of the attachment being insured by reason of the hooks 60 which engage the top edge portion of the pail, such hooks also assisting in holding the filter cloth.

No particular means are necessary to hold 65 the attachment in such position that pres- sure may be exerted against the outside of the pail as the inherent resilience of the strip 13 is sufficient for the purpose.

Referring particularly to Fig. 3, it will 70 be noted that the band 13' is provided with a number of inwardly projecting points 21 adapted to serve the same purpose as the hooks 14 of the first form of the device, these projections being formed preferably by driv- ing the material inwardly. 75

In this form of the attachment the device 80 will be held in position on the pail when the filter cloth is stretched over the open top, by reason of the engagement of the project- ing points of the attachment in the material of the filter cloth.

Either form of device is equally well 85 adapted to serve the purpose for which it was designed; that is, to insure clean milk and a sanitary means of receiving the milk in a pail.

Having thus described my invention, I claim as new, and desire to secure by Letters Patent:—

As a new article of manufacture, an at- 90 tachment for holding a filter cloth on a milk pail, comprising a single strip of resilient material having overturned ends lying adj- acent each other, and a plurality of hooks extending upwardly from the said strip of 95 material, the hooks being adapted to engage the edge portion of the pail.

In testimony whereof I have signed my name to this specification in the presence of two subscribing witnesses.

JOHN A. BLAIR.
